DESIGN FOR A CASING FOR STAPLE MACHINES

Lester L. Wheeler, Norwalk, Conn., and William H. Gref, East Greenwich, R. I., assignors to The E. H. Hotchkiss Company, Norwalk, Conn., a corporation of Connecticut

Application July 21, 1937, Serial No. 70,562

Term of patent 7 years

To all whom it may concern:

Be it known that we, Lester L. Wheeler and William H. Gref, both citizens of the United States, residing at Norwalk, county of Fairfield, State of Connecticut, and East Greenwich, county of Kent, State of Rhode Island, have invented a new, original, and ornamental Design for a Casing for Staple Machines, of which the following is a specification, reference being had to the accompanying drawing, forming part thereof.

Fig. 1 is a side elevation of a casing for staple machines, showing our new design, and

Fig. 2 is a top plan view thereof.

We claim:

The ornamental design for a casing for staple machines, substantially as shown.

LESTER L. WHEELER.
WILLIAM H. GREF.
